FIRE EXTINGUISHER

Edward R. Bork, Dayton, Ohio, assignor to The Fyr-Fyter Company, Dayton, Ohio, a corporation of Ohio

Application April 11, 1949, Serial No. 86,691

9 Claims. (Cl. 169—31)

1

This invention relates to fire extinguishers, and more particularly to a pressure cartridge unit adapted for use in a fire extinguisher.

In fire extinguishers employing a pressure cartridge, it is a common practice for the cartridge to incorporate a removable cap which is secured on the cartridge and which incorporates a frangible sealing disk overlying and normally sealing the outlet from the cartridge, together with the necessary piercing pin and associated mechanism to rupture the disk and meter the outflow of gas therefrom. Both the cartridge and the cap are relatively expensive and are usually returned in order to obtain a recharge. This necessitates not only the added expense of returning the cartridges and caps following each operation and the accompanying handling thereof by the manufacturer, but unless duplicate supplies have been provided, makes the equipment inoperative during this interval. A typical construction of this type is that shown in the patent to Wright No. 1,976,056 issued to the assignee of this application.

The present invention relates to an extinguisher of this type, but in which the pressure cartridge is such that it need not be returned for recharge, being intended for a single use after which it may be thrown away. The cartridge incorporates a rupturing member which is fully and adequately enclosed and protected against access of moisture or other foreign matter prior to operation so that it retains its original sealed condition indefinitely and which affords proper and controlled metering of the flow of gas upon operation so that the desired pressure condition will be obtained throughout the operation without excessive pressure or objectionable freezing up of the gas outlet. In addition the construction is relatively simple and inexpensive and such that the entire device may economically be discarded after a single use. Thus there is no necessity to return anything for recharge and by merely having spare charge available, the spent extinguisher may be immediately restored to operative condition.

It is accordingly one of the principal objects of the present invention to provide a pressure cartridge unit adapted for use in a fire extinguisher which is simple to produce and install, which is reliable in operation even after standby for long periods of time, and wherein the component parts are of simple construction such that the unit can be produced economically for one-time use and then disposed of without refilling.

Another object of the invention is to provide

2

such a pressure cartridge unit which includes a metering orifice so located and arranged in the unit that it is sealed against dirt and moisture at all times prior to use and is automatically opened for discharge simultaneously with the opening of the cartridge itself.

It is also an object of the invention to provide such a pressure cartridge unit which includes a plunger for rupturing and penetrating the cartridge to release the gas therefrom, and more particularly to provide such a unit wherein the plunger includes an integral portion which seals against access of dirt and moisture to the metering orifice prior to use and which automatically moves from its sealing position allowing free outflow of the gas simultaneously with its rupturing action.

Other objects and advantages of the invention will be apparent from the following description, the accompanying drawing and the appended claims.

In the drawing:

Fig. 1 is a view in side elevation, partly broken away and in vertical section, showing a fire extinguisher embodying a pressure cartridge unit constructed in accordance with the present invention;

Fig. 2 is a fragmentary and partially exploded section on a larger scale showing the pressure cartridge unit prior to opening of the cartridge;

Fig. 3 is a view similar to Fig. 2 showing the pressure cartridge unit following opening of the cartridge.

Fig. 4 is a detail view in elevation showing the plunger of the unit;

Fig. 5 is an end view of the upper end of the plunger; and

Fig. 6 is an enlarged view of a fragment of Fig. 2.

Referring to the drawing, which illustrates a preferred embodiment of the invention, Fig. 1 shows a fire extinguisher of the pressure cartridge type having a main casing 10 which is provided with a removable cap 11 and a flexible hose 12. The pressure cartridge 13 is supported within casing 10 in a suitable cage including a U-shaped strap 15 riveted to the supporting arms 16 of a socket member 17, this cage being clamped in operative position between the upper end of the casing 10 and the cap 11. The lower end of cartridge 13 includes the filling neck 20, and is received in an apertured plate 21 which is slotted at opposite ends for sliding engagement with the sides of the strap 15 and is supported

on a cup shaped member 22 carried by thumb-

screw 23 threaded through the lower end of strap 15. A plunger 25 is mounted on and extends through the cap 11 and is adapted to move axially to actuate the extinguisher, the upper end of plunger 25 being provided with a movable cap 26 which extends above the upper end of the handle portion of cap 11 for ready access or for engaging the floor when the extinguisher is inverted and bumped down on the floor.

The construction of the pressure cartridge 13 and its associated parts is shown in more detail in Figs. 2 to 6. Referring to Figs. 2 and 6, the upper end of the cartridge is coined to provide an integral web 30 which is thinner than the remaining walls of the cartridge and is readily rupturable to release the gas therefrom. A frusto-conical surface 31 surrounds the upper surface of web 30 to provide a lead-in taper to the web. A cup-shaped shell 33 is press-fitted, shrunk or otherwise secured at 34 over the upper end of the cartridge and extends beyond the cartridge to form a chamber 35 which overlies the web 30, and this shell has a circular hole 36 in the end thereof which is opposite and substantially coaxial with the web 30. The upper end portion 37 of shell 35 is of smaller diameter than the remainder of the shell to fit readily within the center aperture in socket member 17, the shell having a circumferential shoulder 38 which limits the extent of its insertion in member 17.

A plunger 40 extends through the opening 36 in shell 33, and an intermediate portion 41 of this plunger is cylindrical and of a proper diameter for press-fitting within the opening 36 to seal this opening as shown in Fig. 2. For example, satisfactory results have been obtained with the plunger portion 41 having a diameter of .377 inch and the hole 36 having a diameter of .375 inch, and with the axial length of the plunger portion 41 approximately equal to the thickness of shell 33. An enlarged portion 42 of the plunger forms a circumferential shoulder 43 arranged to seat on the inner surface of the end wall of shell 33.

The plunger 40 also includes an inner end portion 44 which is of such diameter as to be capable of readily rupturing and penetrating the web 30 in the end of cartridge 13, the lower end of this plunger 44 being tapered at 45 to guide the plunger in the rupturing operation by cooperating with the lead-in taper 31 to the web. The plunger portion 44 is formed with a central bore 46 which communicates with a cross passage for releasing the gas from within cartridge 13 after rupture of web 30, the cross passage having a narrow portion 47 immediately adjacent bore 46 which forms a metering orifice leading into a radial bore 48 in the enlarged plunger portion 42. For example, the bores 46 and 48 may be $\frac{1}{16}$ inch in diameter, with the metering passage 47 having a diameter of 0.020 inch and being approximately $\frac{3}{32}$ inch in length.

The plunger 40 also includes an outer portion 50 which normally extends above the end of shell 33 to receive the actuating plunger 25 of the extinguisher. One side of the outer plunger portion 50 is formed with a flat 51 to reduce the cross-sectional area of this part of the plunger to sufficiently less than the corresponding area of the opening 36 in the shell to allow free discharge of gas through this opening when the plunger has been driven inwardly of the shell sufficiently to effect rupture and penetration of the cartridge by its inner end portion 44. In addition, the remainder of the plunger portion 50 is relieved with respect to the intermediate portion 41 to provide

5 a transverse shoulder 52 at the upper end of plunger portion 41, satisfactory results having been obtained with the radius of this portion of the plunger approximately .0025 inch less than the radius of the sealing portion 41.

In operation, the pressure cartridge unit comprising the cartridge 13 with the shell 33 and plunger 40 completely sealed with relation thereto is mounted as shown in Fig. 2 with the upper portion 37 of shell 33 received in socket member 17 and with the upper plunger portion 50 extending above the upper end of the shell, the unit being clamped in this position by tightening thumbscrew 23. Prior to use of the device, the relationship of the parts is as shown in Fig. 2, and it will be noted that in this position, the intermediate plunger portion 41 is tightly received in the opening 36 in shell 33, thus effectively sealing the interior of chamber 35, the passages 46, 47 and 48, and the seal 30 against the access of dirt or moisture. The parts may be retained in these positions for long periods of time without any loss in effectiveness even though liquid from the extinguisher may drip or fall thereupon, the operating end of the cartridge thus remaining effectively protected.

In order to use the extinguisher, it is inverted in the usual way and the plunger cap 26 bumped on the floor or ground with sufficient force to 30 drive the plunger 25 against the adjacent end of plunger 40 and force the latter inwardly of the shell. When this occurs, the inner end 44 of the plunger will be driven against web 30 with sufficient force to rupture and penetrate the web, with the sides of the plunger portion 44 seating tightly within the resulting opened end of the cartridge 13 as shown in Fig. 3. The compressed gas will accordingly be released into the passage or bore 46 and then metered through the orifice 47 and bore 48 into the interior of chamber 35. At the same time, the intermediate plunger portion 41 will have been driven inwardly of the shell sufficiently to clear the hole 36, thus opening this hole for unrestricted flow of gas past the flat 51 into the interior of casing 10 to effect discharge of the fire extinguishing material herein through hose 12. During this operation the gas flows out at a controlled rate determined by the accurately formed metering passage 47 which is predetermined so that the gas will flow at a regulated rate such that no objectionable freezing will occur. Since this metering passage is not subjected to dirt or moisture nor to variations in size resulting from the uncertain breaking of a frangible member but remains with the fixed size originally formed, highly satisfactory discharge conditions are obtained.

It will thus be seen that the invention provides a simple and effective construction for a pressure cartridge unit which offers substantial advantages. The unit includes only two component parts in addition to the cartridge, and they are of such simple design and construction that they can be readily manufactured at sufficiently low cost to justify one-time use and disposal of the unit rather than refilling. Although if it is desired to re-use the plunger and shell, this can be done since they are not damaged in use. Assembly and replacement of the unit are also simple and easy, requiring only the insertion of the assembly in the cage, thereby simplifying the assembly and recharging of the extinguisher.

While the form of apparatus herein described constitutes a preferred embodiment of the invention, it is to be understood that the invention

is not limited to this precise form of apparatus, and that changes may be made therein without departing from the scope of the invention which is defined in the appended claims.

What is claimed is:

1. A pressure cartridge unit adapted for use in a fire extinguisher of the character described comprising a sealed cartridge for containing compressed gas, said cartridge having a rupturable portion at one end thereof, a hollow shell tightly secured to said cartridge and extending beyond said end thereof to form therewith a sealed chamber overlying said rupturable portion, said shell having an opening in the outer end thereof opposite said rupturable portion of said cartridge, a plunger extending through said opening and having an inner portion of such diameter as to rupture and penetrate said rupturable cartridge portion to open said cartridge when said plunger is driven inwardly of said shell, said inner portion of said plunger having a restricted passage therein for metering the gas from said cartridge into said chamber following the penetration of said cartridge, said plunger including an intermediate portion adapted to cooperate with said end of said shell to normally seal said opening and to move out of sealing relation with said shell when said plunger is driven inwardly thereof.

2. A pressure cartridge unit adapted for use in a fire extinguisher of the character described comprising a sealed cartridge for containing compressed gas, said cartridge having a rupturable portion at one end thereof, a hollow shell tightly secured to said cartridge and extending beyond said end thereof to form therewith a sealed chamber overlying said rupturable portion, said shell having an opening in the outer end thereof opposite said rupturable portion of said cartridge, a plunger extending through said opening and having an inner portion of such diameter as to rupture and penetrate said rupturable cartridge portion to open said cartridge when said plunger is driven inwardly of said shell, said inner portion of said plunger having a restricted passage therein for metering the gas from said cartridge into said chamber following the penetration of said cartridge, said plunger including an intermediate portion adapted to cooperate with said end of said shell to normally seal said opening and to move out of sealing relation with said shell when said plunger is driven inwardly thereof, said plunger including an outer portion of substantially less cross-sectional area than said opening to provide for free discharge of gas from said chamber through said opening following said movement of said plunger.

3. A pressure cartridge unit adapted for use in a fire extinguisher of the character described comprising a sealed cartridge for containing compressed gas, said cartridge having a rupturable web at one end thereof, a hollow shell received over said end of said cartridge and tightly secured thereto to form therewith a sealed chamber overlying said web, said shell having an opening in the outer end thereof opposite said web, a plunger having an intermediate portion tightly received in said opening to seal the same, said plunger including an inner portion within said chamber and an outer portion, said inner portion being of such diameter as to rupture and penetrate said web to open said cartridge when said plunger is driven inwardly of said shell, said inner portion of said plunger having a restricted passage therein for metering the gas from said cartridge into said chamber following the pen-

tration of said web, and said outer portion of said plunger being of substantially less cross-sectional area than said intermediate portion to provide for free discharge of said gas from said chamber through said opening.

4. A pressure cartridge unit adapted for use in a fire extinguisher of the character described comprising a sealed cartridge for containing compressed gas, said cartridge having a rupturable web at one end thereof, a hollow shell tightly secured to said cartridge and extending beyond said end thereof to form therewith a sealed chamber overlying said web, said shell having an opening in the outer end thereof opposite said web, a plunger including a portion tightly received in said opening to seal the same, said plunger having an inner portion within said chamber of such diameter as to rupture and penetrate said web to open said cartridge when said plunger is driven inwardly of said shell, said inner portion of said plunger having a restricted passage therein for metering the gas from said cartridge into said chamber following the penetration of said web, said sealing portion of said plunger being of such dimensions as to move out of said opening for free discharge of gas therethrough from said chamber when said inner portion of said plunger has been driven inwardly of said shell to penetrate said web.

5. A pressure cartridge for use in a casing containing material adapted to be discharged upon development of gas pressure therein following release of gas from said cartridge which comprises a weakened wall portion of said cartridge capable of being ruptured, a shell in sealed relation on said cartridge enclosing said wall portion, a plunger carried by said shell in sealed relation therewith and in position to rupture said wall when driven thereagainst, said plunger having a rupturing portion adapted to seal against the opening in said cartridge wall upon being driven therethrough, a metering passage extending through said plunger for controlling the flow of gas from said cartridge into the interior of said shell, and means forming a discharge passage from said shell opening upon actuation of said plunger.

6. A pressure cartridge unit for use in a casing containing material adapted to be discharged upon development of gas pressure therein following release of gas from said unit, comprising a cartridge having a weakened wall portion capable of being ruptured, a shell secured to said cartridge to form therewith a sealed chamber overlying said weakened wall portion, said shell having an opening therein, a plunger mounted in said opening to seal the same and including a portion adapted to rupture said weakened wall portion when driven thereagainst, said plunger including also a portion in position to be engaged from outside said shell for driving said plunger against said cartridge, said plunger having a restricted passage therein for metering the contents of said cartridge into said chamber following rupture of said wall portion by said plunger, and said plunger being proportioned to unseal said opening in said shell upon being driven into rupturing relation with said cartridge to effect free discharge of the contents of said cartridge from said chamber.

7. A pressure cartridge unit adapted for use in a fire extinguisher of the character described comprising a sealed cartridge for containing compressed gas, said cartridge having a rupturable portion at one end thereof, a hollow shell re-

ceived over said end of said cartridge and tightly secured thereto to form therewith a sealed chamber, said shell having an opening in the outer end thereof opposite said rupturable portion of said cartridge, a plunger having an intermediate portion tightly received in said opening to seal the same, said plunger including an inner portion within said chamber and an outer portion, said inner portion being hollow and of such diameter as to rupture and penetrate said cartridge when said plunger is driven inwardly of said shell, said inner portion of said plunger having a metering passage connecting said hollow portion thereof with said chamber, and said outer portion of said plunger being of substantially less cross-sectional area than said intermediate portion to provide for free discharge of gas from said chamber through said opening when said intermediate plunger portion is driven inwardly of said shell.

8. A pressure cartridge unit adapted for use in a fire extinguisher of the character described comprising a sealed cartridge for containing compressed gas, said cartridge having a rupturable web at one end thereof, a hollow shell tightly secured to said cartridge and extending beyond said end thereof to form therewith a sealed chamber overlying said web, said shell having an opening in the outer end thereof opposite said web, a plunger including a portion tightly received in said opening to seal the same, said plunger having an inner portion within said chamber of such diameter as to rupture and penetrate said web to open said cartridge when said plunger is driven inwardly of said shell, said inner portion of said plunger having a restricted passage therein for metering the gas from said cartridge into said chamber following said penetration of said web, said sealing portion of said plunger being of such dimensions as to move out of said opening for free discharge of gas therethrough from said chamber when said inner portion of said plunger has been driven sufficiently

5 inwardly of said shell to penetrate said web, and a shoulder on said plunger inwardly of said sealing portion in position to seat on the inner surface of said end of said shell for preventing withdrawal of said plunger from said shell.

- 10 9. A pressure cartridge unit adapted for use in a fire extinguisher of the character described comprising a sealed cartridge for containing compressed gas, said cartridge having a readily rupturable web at one end thereof, a hollow shell tightly secured to said cartridge and extending beyond said end thereof to form therewith a chamber overlying said web, said shell having a circular opening in the outer end thereof opposite said web, a plunger including a cylindrical portion tightly received in said opening to seal the same, said plunger having an inner portion within said chamber of such diameter as to rupture and penetrate said web to open said cartridge when said plunger is driven inwardly of said shell, said plunger having a central bore open at said inner end thereof and having also a restricted passage connecting said bore with the interior of said chamber for metering the gas from said cartridge into said chamber following said penetration of said web, and said plunger having an outer portion of smaller cross-sectional area than said sealing portion to provide for free discharge of gas from said chamber through said opening in said shell following said rupture of said web.
